UNITED STATES PATENT OFFICE.

JOHN E. MILLER, OF PITTSBURG, PENNSYLVANIA, ASSIGNOR TO GEORGE DUNCAN & SONS, OF SAME PLACE.

DESIGN FOR TABLE-WARE.

SPECIFICATION forming part of Design No. 19,871, dated June 3, 1890.

Application filed May 2, 1890. Serial No. 350,384. Term of patent 3½ years.

To all whom it may concern:

Be it known that I, JOHN E. MILLER, of Pittsburgh, in the county of Allegheny and State of Pennsylvania, have invented a new and original Design for Table-Ware, of which the following is a full, clear, and exact description, reference being had to the accompanying drawings, forming part of this specification, in which—

- 10 Figure 1 is a side view of a bottle embodying my design. Fig. 2 is a cross-section on the line II II of Fig. 1. Fig. 3 is a side view of a bowl embodying the design.

The design consists of a hollow article of 15 table-ware, the shape of whose body is substantially as hereinafter described, and as shown in the drawings. The horizontal section of the body of the article, as bounded by imaginary lines extending from corner to corner, is substantially rectangular. On the side

of the article are panels *b*, which are less prominent than the corners, and which are made of laterally-curved form conforming to the curvature and shape of the interior of the article, and which peripherally are of substantially the form shown in the drawings. The fact that the panels thus conform to the interior shape of the article, while the corners are prominent and are of substantially rectangular form in cross-section, gives the article a peculiar and distinctive appearance. 25 30

I claim—

The design for glassware, substantially as herein shown and described.

In testimony whereof I have hereunto set my hand this 26th day of April, A. D. 1890.

JOHN E. MILLER.
